DESIGN FOR A WAFFLE MOLD OR THE LIKE

Edward S. Preston, Hinsdale, Ill., assignor to Chicago Electric Manufacturing Company, Chicago, Ill., a corporation of Illinois

Application October 8, 1937, Serial No. 72,081

Term of patent 7 years

To all whom it may concern:

Be it known that I, Edward S. Preston, a citizen of the United States, residing at Hinsdale, Du Page County, Illinois, have invented a new, original, and ornamental Design for a Waffle Mold or the like, of which the following is a specification, reference being had to the accompanying drawing forming a part thereof.

The dominant feature of my design resides in the arrangement of the parallel ornamental stripes or steps as shown.

I claim:

The ornamental design for a waffle mold or the like, substantially as shown and described.

EDWARD S. PRESTON.
